FLAT KNITTING MACHINE

Howard K. West, Lansdale, Pa., assignor to Dex-
dale Hosiery Mills, Lansdale, Pa., a corporation
of Pennsylvania

Application August 19, 1942, Serial No. 455,286

13 Claims.

(Cl. 66—82)

This invention relates to knitting machines, particularly fine gauge flat knitting machines of the "Cotton" type such as are extensively used in the manufacture of full fashioned hosiery and the like.

In the operation of such knitting machines considerable difficulty is experienced through needle breakage, the correction of which entails loss of valuable time with corresponding curtailment in output. The difficulty is due to various causes, including frailty of the needle beards, crystallization of the metal through repeated rapid flexing of the beards, and through moving frictional contact of the beards under heavy pressure with the presser ledge incident to stitch formation, which latter action is in turn attended by the formation of grooves in said ledge by the needle beards.

The chief aim of my invention is to overcome the several above mentioned drawbacks, which objective is realized in practice as hereinafter more fully set forth, through provision, in lieu of the usual spring beard needles, of needles with plain short rigid hooks, and separately actuated cooperative instrumentalities in the form of beard points which, in addition to performing the functions of the usual needle beards, control the yarn to insure its being taken by the end needles to make certain the formation of perfect selvages, and which, during stitch formation, are interposed between the needles and the presser ledge and are buttressed by said ledge as the needles are lightly pressed against them; and through the further provision of actuating means by which the period of sliding contact of the points with the ledge during each stitch forming cycle is reduced to a minimum.

A further aim of my invention is to make possible the actuation of the beard points from above the needles and to provide for their retraction automatically during fashioning phases of the knitting when the usual loop transfer points come into operation. The last mentioned objective I also attain in practice as later on more fully disclosed herein through provision of simple additional mechanism which is easily attached to existing machines and which does not in any way affect the normal functioning of the machine.

My invention is further concerned with provisions which will permit the needle beard points to be moved to an inactive out-of-the-way position when access to the needles is desired for welt turning or other purposes; as well as with the provision of safety means which will prevent

starting of the machine as long as the hook covering points are thus retracted, thereby to preclude press-offs.

Other objects and attendant advantages will appear from the following description of the attached drawings, wherein

Fig. 1 is a fragmentary view partly in end elevation and partly in cross section of a flat knitting machine conveniently embodying the present improvements.

Fig. 2 is a fragmentary broken out horizontal plan section taken as indicated by the angled arrows II—II in Fig. 1.

Fig. 3 is a fragmentary transverse sectional view of the machine taken as indicated by the angled arrows III—III in Fig. 2.

Fig. 4 is a fragmentary detail view in section taken as indicated by the angled arrows IV—IV in Fig. 1.

Fig. 5 is a detail view in side elevation showing certain of the rotary cams by which the knitting instrumentalities of the machine are actuated.

Fig. 6 is a large scale front perspective view of one of the special hook needles which I have devised for utilization in my improved knitting machine.

Figs. 7 and 8 are cross sectional views of the needle on a still larger scale, taken respectively as indicated by the angled arrows VII—VII and VIII—VIII in Fig. 6.

Figs. 9 and 10 are large scale front and rear perspective views respectively of one of the novel beard points provided for cooperation with the needles in stitch formation.

Figs. 11 and 12 are cross sectional views of the beard point taken as indicated respectively by the angled arrows XI—XI and XII—XII in Fig. 9 and drawn to a still larger scale.

Figs. 13, 14, 15, 16, 17, 18 and 19 are large scale fragmentary detail views corresponding to Fig. 3 showing successive positions of various elements of the machine which cooperate in stitch formation.

Figs. 20 and 21 are detail cross sectional views taken as respectively indicated by the angled arrows XX—XX and XXI—XXI in Fig. 16.

Fig. 22 is a fragmentary view partly in section and partly in elevation like Fig. 3 showing how the beard points are retracted during the fashioning phases of the knitting.

Figs. 23 and 24 are detail views showing how the yarn is controlled by the needle beard points at one of the end or selavage needles; and

Fig. 25 is a horizontal detail plan section taken as indicated by the arrows XXV—XXV in

Fig. 23, the plane of the section of the latter illustration being in turn indicated by the angled arrows XXIII—XXIII in Fig. 25.

The knitting machine herein shown for convenience of exemplifying my invention is of the single unit type constructed generally after the manner disclosed in U. S. Patent No. 1,982,991, granted to Kenneth Howie and Charles C. Krieble on December 4, 1934. Here, as in the patent, the main cam shaft 12 of the machine is journaled in suitable bearings on the spaced end frames 13 between which extend the usual upper frontal beam or bed 15 and the intermediate upper beam 16 which latter supports the bed 17 for the sinkers 18 as well as for the jacks 19 through which the sinkers are actuated in a well known manner, by means not illustrated. Arranged immediately below the sinkers are the respectively associated knockovers 20 which are likewise suitably operated. Also journaled in bearings on the end frames 13 above the cam shaft 12 is a rock shaft 21 whereto is affixed a pendent arm 22 with a roller (not shown) which runs in contact with a cam (not shown) on said cam shaft, and horizontal forward projecting arms 26 whereto the carrier 27 for the needle bar 28 of the machine is pivoted at 29. Through the medium of the connections just described, the usual up and down movements are imparted to the needle bar 28 as required incident to stitch formation. The attendant in-and-out movements of the needle bar 28 are induced through another pair of arms such as the one shown at 30 which is loose on the shaft 21 and carries a roller 31 which bears on the periphery of a rotary cam 32 on the cam shaft 12. Projecting laterally from each arm 30 is a stud 33 which is engaged by the hook end of a horizontal link 34 pivotally connected to a pendent arm 35 affixed to one of the pivots 29. As ordinarily, the machine is provided with loop transferring points 36 which are used in the fashions phases of the knitting, and which are fixed in a holder 37. As ordinarily, the holder 37 is suspended from a rod 38 carried by end brackets 39 which are in turn connected to a parallel rod 40 supported by dipper arms wherof one is partly shown at 41 in Fig. 3. These arms 41 are actuated in a well known may through drop links 42, which at their lower ends are connected to horizontal arms 43 on a rock shaft 44 immediately alongside the rock shaft 21.

In adapting my invention to a knitting machine of the type just briefly described, I substitute in the bar 28 in place of the usual spring beard needles, needles such as shown at 45 having short rigid hooks 45a at their tops. As shown to the best advantage in Fig. 6, the hook needles are fashioned from round wire, with laterally turned anchorage butts 45b (like those of ordinary spring beard needles) at their bottom ends. Somewhat below the hook 45a, the wire is slotted as at 45c to provide a longitudinally extending V-section frontal groove (see Fig. 7), and below the groove the shank of the needle is flattened as at 45d in Figs. 6 and 8 with incidental formation of shoulders at 45e, the flattened portion below said shoulders being wider than that above, and extending down almost to the butt 45b. From Fig. 3, it will be noted that the wide flat lower portion of the needle shank is almost wholly embedded in the needle bar 28 as a result of which the needle is securely held, while the projecting upper portion of the needle is free above the needle bar and capable of slight flexure in the plane of the butt 45b. For individual co-

operation with the needles 45, in stitch formation, I provide special hook covering beard instrumentalities or points 47, such as shown in detail in Figs. 9-12, each having a beard portion 47a at one end and a laterally bent anchorage butt 47b at the other end. Like the hook needles 45, the points 47 are fashioned from round wire stock, but to obtuse angular configuration (as viewed from the side) with a knee bend at 47c. The beard portion 47a of the point is slotted as at 47d to provide a longitudinal U-groove, see Fig. 12, for reception of the needle hook 45a in the manner shown in Figs. 16 and 20, and its shank portion is flattened as at 47e in the plane of the butt 47b for greater security against yielding torsionally in its holder bar 49, see Fig. 3. The described construction allows slight flexure of the beard end 47a of the point about the knee bend at 47c.

During stitch formation, the tapered ends of the beard points 47 enter the grooves 45c in the shanks of the needles 45 after the manner of the beards of ordinary spring needles, and as shown in Fig. 21.

As shown in Figs. 1-3, the supporting bar 49 for the beard points 47 is arranged longitudinally of the machine, and at its ends has rearwardly projecting horizontal arms 50 with laterally and outwardly extending fulcrum trunnions 51 engaged in bearing bosses 52 on the parallel side members 53a of a horizontal carriage 53, said side members being confined to endwise sliding movement in guides 54. As further shown in Figs. 1-3, integrally formed pendent sleeves 55 on the guides 54 are clamped to a shaft 56 journaled in bearing brackets 57 which are separately secured to the rearward projections 13a of the end frames 13 of the machine. Rocking movements are imparted to the shaft 56 through an attached arm 58 having a roller 59 at its free end running on the periphery of a special cam 60 on the main cam shaft 12 of the machine, such engagement being yieldingly maintained by a tension spring 61 (Fig. 1). The carriage 53 is urged forwardly in its guides 54 by springs 62, each of which is secured at one end to a cross bar 63 connecting the side members 53a of said carriage, and at the other end to a fixed anchorage 65 on the frontal bed 15 of the machine. From Fig. 2 it will be observed that the inward movement of the carriage is limited by engagement of adjustable stop screws 66 at the rear ends of the side members 53a (Figs. 2 and 3) with the corresponding ends of the guides 54. Due to the engagement of spring pressed stop pins 67 in upstanding arms 68 affixed to the trunnions 51 respectively with notches 69 in upstanding sector projections 70 on the bearing bosses 52, the beard point bar 49 is normally maintained in the position shown in full lines with its rearward arms 50 in the planes of the members 53a. At their tops the stop pins 67 are formed with finger grasps 71 whereby they may be lifted from engagement with the notches 69 in the sectors 70 to enable the point bar 49 to be swung upwardly and rearwardly to the position in which it is shown in dot-and-dash lines in Fig. 3 when access is necessary to the needles 45, as for example in turning welts. When moved as just explained, the point bar 49 is held against accidental displacement through engagement of the inner ends of the stop pins 67 with smaller notches 72 in the sectors 70. Extending inwardly of the machine from the bearing bosses 52 on the side members 53a of the carriage 53 are arms 75 with rollers 76 at their

free ends which are adapted to engage the rear edges of upstanding projections 77 on the needle bar 28 as the beard point bar 49 is vertically oscillated during stitch formation as presently explained. Incident to the fashioning phases of the knitting, as the links 42 are moved downward, cam pieces 78 attached to them engage rollers 79 on the trunnions 51 of the carriage 53, thereby to effect retraction of said carriage 53 with the beard points 47 out of the path of the transfer points 36 as the latter descend in fashioning operations, as shown in Fig. 22. The cam for controlling the beard points during the fashioning phases is shown at 60 in Figs. 3 and 5 as mounted on the cam shaft 12 alongside the cam 60.

In order to obviate press-offs in the event that the machine attendant leaves the point bar 49 swung up in its inoperative position after turning welts, I have provided a safety means which will prevent starting of the machine at such times. As best shown in Figs. 1 and 22, this safety means includes a detent 81 which is affixed to the inner end of a short shaft 82 journaled in the right-hand side frame 13, and which is adapted to engage the teeth of a pinion 83 embodied in the drive mechanism of the machine and in mesh with the gear 84 on the cam shaft 12. To the outer end of the shaft 82 is in turn affixed an arm 85 which reaches upward, and of which the top end contacts with a finger 86 on the trunnion 51 at the corresponding end of the machine. Normally with the beard point bar 49 in the active position in which it is illustrated in Fig. 1, the detent 81 is held raised out of engagement with the gear pinion 83. On the other hand, when the beard point bar 49 is swung counter-clockwise to the inoperative position shown in dot-and-dash lines in Fig. 3, the finger 86 will be correspondingly moved and allow the detent 81 to engage the teeth of the pinion 83.

The operation of the machine improved in accordance with my invention, is as follows:

In Figs. 1 and 3 the hook needles 45 are in their fully elevated positions, the beard points 47 fully raised, and the sinkers 18 fully retracted at the beginning of a loop-forming cycle in a knitting phase, the yarn Y having been laid on the nibs of said sinkers to the front of said needles by the horizontally reciprocating carrier which is indicated at 87 in Fig. 1, and which is also shown in Figs. 23-25. Fig. 13 illustrates the next step in the cycle in which the sinkers 18 have just been advanced to kink the newly laid yarn Y about the shanks of the needles 45, a portion of the previously knit web W being shown as lying in the interval between said sinkers and the knock-overs 20, and the beard points 47 having been lowered by the initial easy slope 60x of the cam 60 (Fig. 5) to a level slightly above the needles with the straight backs of their end portions substantially in line with the straight front portion of the presser ledge 17a. Thereupon the needles 45 and beard points 47 descend at different rates through the position shown in Fig. 14, the points moving faster by reason of the sharp rise 60a on cam 60 (Fig. 5). At the same time, the needles 45 are caused to swing inward of the machine as ordinarily. These concurrent movements continue until the stage shown in Fig. 15 is reached with the straight backs of the point ends 47a contacting the straight front of the presser ledge 17a, with the ends of the points in the grooves 45c of the needles 45, with the hooks 45a of the needles buried in the grooves 47d of

said points, and the newly sunk bights of the yarn Y trapped in the closed eyes jointly formed by said needles and said points. From then on, due to the short but gradual rise 60b on the cam 60 (Fig. 5), the points 47 are caused to descend at a uniform rate with the needles 45 to the position illustrated in Fig. 16, with the ends of the points penetrating the loops L' of the previously formed course of the fabric on the knock-overs. During the last described step, the lateral position of the points 47 with respect to the needles 45 is accurately controlled through co-operation of the rollers 79 on the carriage 53 with the cam projection 77 on the needle bar 28 in such a manner that the lateral pressure exerted between the needles and the points and between the latter and the presser ledge 17a is very slight—just sufficient to insure needle hook sheathing with penetration of the old loops L' by the points, and row aligning of said points as shown in Figs. 20 and 21 for obtainment of uniformity in the size of the new loops under formation. It will moreover be observed that during the last described step, the points 47 have straight line contact with the front of the presser ledge 17a. This is made possible through ability of the needles to flex at their shoulders 45e and the points to flex at their knee bends 47c in adapting themselves one to the other. By reason of the immediately foregoing and the short period of straight line contact between the points 47 and the presser ledge 17a, it will be evident that wear on the said points and ledge is reduced to a minimum. At this stage in the loop forming cycle, it will be further noted from Fig. 17 that the points 47 also function as strippers during retraction of the sinkers 18, by holding the loops L in the manner shown. This action is advantageous in that it obviates yarn rupture as often happens ordinarily when the sizing causes the yarn to stick to the top edges of the sinker nibs. Due to the dwell 60c at the crest or high spot of the cam 60 (Fig. 5), the points 47 are caused to rest for a short time in their lowest position as shown in Fig. 16 while the needles begin moving laterally outward from engaging contact and at the same time are further depressed to draw the new loops L off the nib ends of the receding sinkers 18. When the needles 45 have reached the lowest level in their descent with the new loops L drawn through the previously formed loops, the points 47 begin to rise as shown in Fig. 18 with attendant advance of the knockovers to cast said new loops. In Fig. 19, the knockovers have been fully advanced preparatory to the ensuing projection of the sinkers 18 and rise of the needles 45, as ordinarily, for the initiation of the next loop forming cycle of the machine. Referring again to Fig. 5, the cam 60 is provided with a sudden drop at 60d whereby the beard points 47 are given a considerable lead on the needles as they rise together at the completion of each loop forming cycle of the machine, as shown in Fig. 19.

At the region 60e, the cam 60 has an edge portion coinciding with the cam 60, whereby the beard points 47 are controlled during the fashioning phases of the machine, said region constituting the cross-over point for the roller 59 on the arm 58 when the cam shaft 12 is axially shifted as usual from its knitting phase position to its fashioning phase position, and vice versa. With the roller 59 riding on the concentric low portion 75 of the cam 60 during the fashioning phases, the

beard points 47 will be held in the retracted or inactive position in which they are illustrated in Fig. 22 as already explained, where they will not interfere with lateral loop displacement between needles by the transfer points 36, which operation can thus be accomplished in the usual and well known way.

Figs. 23-25, show how my improved beard points also serve as a means for controlling the knitting yarn Y to insure the formation at all times of selvage loops on the end or selvage needles. In Figs. 23, 24 the selvage needle is indicated at 45x and the cooperating beard point at 47x, the yarn carrier 87 having stopped over the sinker (divider 18y) immediately beyond said end needle in Fig. 25. By virtue of being positioned in front of the end needle 45x and of extending well above it as shown in Fig. 23 at the time the selvage loop L2 is about to be drawn off the nib of sinker 18x immediately inward of the needle, the point 47x by cooperation with the next adjacent point 47y outwardly thereof in the series, will hold the strand of loose yarn Y which extends from the carrier 87 in restraint, thereby preventing it from ballooning and precluding springing of the new selvage loop out of the needle hook until said loop has been drawn into the previous selvage loop L3 of the web W as shown in Fig. 24, as often happens in ordinary flat machines when high-twist or other lively yarns are used in the knitting.

From the foregoing it will be apparent that my invention is in the form of a simple and relatively inexpensive attachment which is applicable to standard types of flat knitting machines without entailing any changes in their construction except for substitution of hook needles in place of the usual spring beard needles, and moreover, without affecting the normal mode of operation of such machines. By providing for the operation of the beard points from above the needles, it will be seen that I avoid complicity in the actuating mechanism therefor and fouling, or interference with the closely crowded needle, sinker and knockover control mechanisms in the lower part of the machine. It will be further seen that the design and allocation of the beard point actuating mechanism is such as to allow ready welt turning, as well as observation, at all times, of the work as it is horizontally drawn forward in the usual way during its formation by the take-up (not shown) of the machine.

Having thus described my invention, I claim:

1. In a knitting machine, a presser ledge; a series of hook needles; means for moving the needles up and down and in and out relative to the presser ledge; a series of beard points; and mechanism for actuating the points to interpose them from above between the presser ledge and the needles and to cause them to cooperate with the needles during the loop forming cycles of the machine, including a holder for the points, and a support pivoted for up and down swinging movement in which the holder is confined to reciprocation for lateral movement with the needles relative to the presser ledge.

2. In a knitting machine, a presser ledge; a series of hook needles; means for moving the needles up and down and in and out relative to the presser ledge; a series of beard points; and mechanism for actuating the points to interpose them from above between the presser ledge and the needles and to cause them to cooperate with the needles during the loop forming cycles of the

machine, including a holder for the points, a support pivoted for up and down swinging movement in which the holder is confined to reciprocation for lateral movement with the needles relative to the presser ledge, a rotary shaft, a cam on said shaft, and interposed operating connections between said support and said cam.

3. In a knitting machine, a presser ledge; a series of hook needles; means for moving the needles up and down and in and out relative to the presser ledge; a series of beard points; and mechanism for actuating the points to interpose them from above between the presser ledge and the needles and to cause them to cooperate with the needles during the loop forming cycles of the machine, including a holder for said points, a support pivoted for up and down swinging movement in which the holder is confined to reciprocation for lateral movement with the needles relative to the presser ledge; and means whereby the holder is connected to the guide with capacity for retraction to an inoperative position to permit access to the needles when necessary.

4. In a knitting machine, a presser ledge; a series of hook needles; means for moving the needles up and down and in and out relative to the presser ledge; a series of beard points; and mechanism for actuating the points to interpose them from above between the presser ledge and the needles and to cause them to cooperate with the needles during the loop forming cycles of the machine, including a holder for said points, a support pivoted for up and down swinging movement in which the holder is confined to reciprocation for lateral movement with the needles relative to the presser ledge; means whereby the holder is connected to the guide with capacity for retraction to an inoperative position to permit access to the needles when necessary; and safety means automatically rendered effective when the holder is so retracted to prevent operation of the machine.

5. In a knitting machine, driving mechanism; a presser ledge; a series of hook needles; means for moving the needles up and down and in and out relative to the presser ledge; a series of beard points; and mechanism for actuating the points to interpose them from above between the presser ledge and the needles and to cause them to cooperate with the needles during the loop forming cycles of the machine, including a holder for said points, a support pivoted for up and down swinging movement in which the holder is confined to reciprocation for lateral movement with the needles relative to the presser ledge; means whereby the holder is connected to its support with capacity for retraction to an inoperative position to permit access to the needles; and safety means for automatically locking the drive mechanism of the machine against movement when the holder is so retracted.

6. In a knitting machine, a presser ledge; a series of hook needles; means for moving the needles up and down and in and out relative to the presser ledge; a series of beard points; and mechanism for actuating the points to interpose them from above between the presser ledge and the needles and to cause them to cooperate with the needles during the loop forming cycles of the machine, including a holder for said points, a support pivoted for up and down swinging movement in which the holder is confined to reciprocation for lateral movement with the needles relative to the presser ledge; and means whereby the holder is connected to the guide with capacity for retraction to an inoperative position to permit access to the needles; and safety means for automatically locking the drive mechanism of the machine against movement when the holder is so retracted.

dles relative to the presser ledge, means for yieldingly urging the holder forwardly in the support toward the needles, and cam means movable with the needles and influential upon the holder to move it in opposition to said yielding means for maintenance of the points in proper cooperative relation laterally with the needles during loop formation.

7. In a knitting machine, a series of hook needles; a series of beard points to cooperate with the needles in loop formation; a series of transfer points to cooperate with the needles in fashioning phases; means for changing the machine from knitting to fashioning phases of operation; and means automatically operated during transition of the machine from the knitting phases to render the beard points inoperative and to move them to a position out of the way of the transfer points.

8. In a knitting machine, a presser ledge; a series of hook needles; means for moving the needles up and down and in and out relative to the presser ledge; a series of beard points; mechanism for actuating the points to interpose them from above between the presser ledge and the needles and to cause them to cooperate with the needles during stitch forming cycles of the machine; means for changing the machine from knitting to fashioning phases and vice versa; a series of transfer points to cooperate with the needles during the fashioning phases; and means automatically actuated during transition of the machine from the knitting phases to the fashioning phases to prevent operation of the beard points and to move them to a position where they will be out of the way of said transfer points during such fashioning phases.

9. In a knitting machine, a presser ledge; a series of hook needles; means for moving the needles up and down and in and out relative to the presser ledge; a series of beard points; a rotary cam shaft which is axially shiftable to change the machine from knitting phases to fashioning phases, and vice versa; a rotary cam on the cam shaft instrumental in actuating the points during knitting phases to interpose them between the presser ledge and the needles and to cause them to operate with the needles in loop formation; a series of transfer points to cooperate with the needles during the fashioning phases of the machine; another cam on the cam shaft influential when the machine is in its fash-

ioning phases to prevent actuation of the beard points and to move said points to a position where they will be out of the way of said transfer points during the fashioning phases.

- 5 10. In a knitting machine, a series of flexible hook needles; a corresponding series of knockovers; a presser ledge; means for moving the needles up and down and laterally toward and away from the presser ledge; a series of beard points having flexibly-supported grooved end portions with straight backs for sheathing the needle hooks incident to loop formation; and actuating means operative during each loop forming cycle when the needles are raised and 15 remote from the presser ledge to first move the points from a position beyond the needles to a position forward and abreast of the needle hooks with their straight backs in line with the front face of said presser ledge; then to move the 20 points downwardly in unison with the needles at the time when the latter are concurrently moved inward of the machine whereby contact with the points ensues and the backs of the point ends are caused to slide in light straight line contact 25 with the front of the grooved presser ledge until said points have penetrated the previously formed loops on the needle shanks and rest on the knockovers, and immediately, as the needles recede after having drawn new loops through said previously formed loops, to withdraw the points from the region of stitch formation and return them to their original positions.

11. A knitting machine according to claim 10, in which the beard points are operated from 35 above the needles.

12. A needle hook-sheathing point for use in a knitting machine such as defined in claim 1, having an anchorage or shank portion, and a grooved hook-sheathing end portion joined to 40 said shank portion by a thinner connecting portion about which flexure can take place.

13. A needle hook-sheathing point for use in a knitting machine such as defined in claim 1, said point being formed from a length of round 45 wire whereof one end part is flattened to provide a rigid anchorage portion, and whereof the other end part is spread and grooved to provide a hook-sheathing portion, and having a relatively thin portion connecting said hook-sheathing portion 50 with said anchorage portion to define a point about which flexure can take place.

HOWARD K. WEST.
